INJECTABLE SOLUTION

Leon Lachman, Summit, N.J., assignor to Ciba Corporation, a corporation of New Jersey
No Drawing. Filed July 15, 1959, Ser. No. 827,146
18 Claims. (Cl. 167—58)

This invention relates to and has for its object the provision of injectable solutions of reserpine and related alkaloids, such as deserpidine and rescinnamine, as well as methods for their preparation.

The provision of injectable solutions of the *Rauwolfia* alkaloids has always posed a stability problem, especially where vial solutions are permitted to remain in that form for long periods before use. Thus, it has been found that such vial solutions of reserpine, are subject to both hydrolytic and oxidation-reduction degradation. Analytical results indicate that the degradation may yield products, such as 3,4,5-trimethoxy benzoic acid, tetrahydroreserpine (tetrahydodeserpidine, tetrahydiorescinnamine, etc.) and isoreserpine (isodeserpidine, isorescinnamine, etc.). The 3,4,5-trimethoxy-benzoic acid normally precipitates and/or results in cloudy mixtures which are, of course, unsuitable for injection.

To overcome the above and related difficulties a formulation type has been developed which will inhibit hydrolysis at the ester linkage of the molecule and will also afford protection against the oxidation-reduction reaction which appears to take place generally in Ring C of the alkaloid molecule. To procure the desired effects according to the invention, it has been found essential to include in the injectable aqueous solution of reserpine (or related alkaloid) a combination of (1) an N-substituted amide (or mixture of such amides) and (2) a non-toxic acid having a pK_a of about 3 to about 5, more particularly of about 3.5 to about 4.5, especially about 4. Also desirably included in the solutions of the invention are non-toxic glycols, either in monomeric form or polymeric form. Such glycols include, *inter alia*, glycol; 1,2-propanediol; 1,2-butanediol, polyalkylene glycols having molecular weights between about 100 and about 20,000 including polyethylene glycols (i.e. Carbowaxes), such as Carbowax 300, Carbowax 1000, Carbowax 1500W, Carbowax 6000, etc. as well as the corresponding polypropylene glycols.

The N-substituted amides which constitute an essential ingredient of the compositions of the invention are preferably N-substituted or N,N-disubstituted amides of lower aliphatic acids, such as formic, acetic, propionic, butyric, sec-butyric, pentanoic, 2-methyl butyric, trimethylacetic, hexanoic, heptanoic, etc., also, chloroacetic acid, chloropropionic acid, dichloroacetic acid, β -hydroxy propionic acid, etc. The substituent on the amide nitrogen is preferably an alkyl substituent, especially a lower alkyl substituent, such as methyl, ethyl, isopropyl, propyl, butyl, hexyl, etc., but may be any other aliphatic substituent, such as β -hydroxyethyl, β -chlorethyl, etc., or an aromatic substituent, such as phenyl, tolyl, chlorophenyl, etc. or an aralkyl substituent, such as benzyl, phenethyl, chlorobenzyl, etc. Where polycarboxylic acids are used, there may be additional N-substituents on the amide nitrogen atoms. Thus, with dicarboxylic acids (particularly lower alkylene dicarboxylic acids), such as succinic acid, adipic acid, etc., one may have up to four substituents, such as lower alkyl substituents, on the amino nitrogen atoms. In addition, N-substituted and disubstituted ureas are included within the purview of the invention, as are the analogous trisubstituted and tetrasubstituted ureas, etc. Thus, ureas, containing the same substituents as those mentioned above, may be employed in the invention. Specific examples of the substituted amides which may be used in the invention are N- or N,N-lower alkyl sub-

2

stituted lower fatty acid amides, such as N-methylacetamide; N,N - dimethylacetamide; N,N - diethylpropionamide; N,N-dibutylpropionamide; N-amylpropionamide; N,N-dimethylbutyramide; N-ethylbutyramide; ureas substituted on at least one nitrogen atom by a hydrocarbon substituent (particularly a lower alkyl substituent), such as N,N-dimethylurea; N,N-dimethylurea; N,N,N',N'-tetramethylurea; N,N-diethylurea; N,N-diethyl thiourea; N,N,N',N'-tetraethylurea; N,N-dipropylurea, etc. One may also use N-mono or poly-substituted (especially lower alkyl substituted) amides of lower alkylene dicarboxylic acids, such as N,N,N',N'-tetramethyl fumaramide; N,N-dimethyl fumaramide; N,N,N',N'-tetramethyl succinamide; N,N'-dimethyl succinamide; N,N'-diisopropyl succinamide; N,N,N',N'-tetramethyl glutaramide; N,N-diethyl adipamide, N-butyl adipamide, etc. In addition, one may use benzene mono and dicarboxylic acid amides wherein at least one nitrogen atom is substituted (especially those wherein the substituents on the nitrogen atom are lower alkyl, e.g. di-lower alkyl phthalamides or tetra-lower alkyl phthalamides). Examples of such compounds are N,N,N',N'-tetramethylphthalamide; N,N'-dimethylphthalamide; N-methyl phthalamide; N,N'-diethyl phthalamide; N,N,N',N'-tetramethyl isophthalamide; N,N,N',N'-tetrabutyl isophthalamide; N,N,N',N'-tetramethyl terephthalamide; N,N-dipropyl terephthalamide; etc. In addition, one may advantageously utilize other amides, such as N-lower alkylated xanthines, e.g. 1,3,7-trimethylxanthine; 1,3,7-triethylxanthine, 1,3-dimethylxanthine; 3,7-dimethylxanthine; etc., or one may use N-substituted amide polymers, such as polyvinyl pyrrolidone, etc.

The non-toxic acids having a pK_a of about 3 to about 5 which are used in the inventive solutions are preferably alkane dicarboxylic acids, especially adipic but also including other acids, such as malic, mandelic, tartaric, lactic, acetic, hippuric, malonic, propionic, etc.

In the compositions of the invention the reserpine (or equivalent *Rauwolfia* alkaloids) may be present in an amount ranging from about 1 to about 10 mg. (preferably about 1 to 5, especially about 2.5 mg.), per milliliter of solution, the N-substituted amide may be present in an amount ranging from about 5 to about 30% (preferably about 10 to 20, especially about 10%) of solution, the glycol may be present in an amount ranging from about 5 to about 30% (preferably about 5 to 15, especially about 5%) of solution, and the acid having a pK_a of about 3 to about 5 may be present in an amount ranging from about 0.5 to about 2%, (preferably 0.5 to 1.5%, especially about 1.0%) adjusted so that no acid precipitates from the solution. [The term "solution" as used above refers, of course, to the final solution prepared for injection].

In addition to the essential components of the injectable solutions, including the water for injection, one may, of course, desirably add other ingredients. Thus, there may, for example, be included antioxidants, such as thiourea, sodium sulfite, sodium metabisulfite, ascorbic acid, cysteine hydrochloride, sodium formaldehyde sulfoxylate; monothioglycerol, thiosorbitol, and chelating agents, such as ethylene diamine tetraacetic acid, in mono, di or tri salt form, especially where the salt forming cations are those of the alkali or alkaline earth group (e.g. trisodium; disodium monocalcium; disodium; monocalcium; monosodium; etc. salts), sodium gluconate, amino acids (e.g. cystein hydrochloride) or any other known chelating agents.

Following are working examples, illustrative of, but in no way intended to limit the present invention. Unless otherwise indicated, all parts, wherever given in the specification, are parts by weight.

3
Example 1

Materials and formula	ml	1000
Reserpine	g	2.500
Adipic acid	g	10.000
N,N-dimethylacetamide	ml	100.000
Ethylenediamine tetraacetic acid monosodium salt	g	0.100
Benzyl alcohol	ml	10.000
Polyethylene glycol 300	ml	50.000
Ascorbic acid	g	0.500
Sodium sulfite	g	0.100
Water for injection, ¹ q.s.	ml	1000.000

¹ Water for injection used is heated to a boil and then nitrogen gas passed through for 30 minutes.

Procedure.—Dissolve the reserpine in the N,N-dimethylacetamide with stirring. Then add the adipic acid and dissolve. Add the polyethylene glycol 300 and benzyl alcohol and mix. Dissolve the sodium sulfite, ascorbic acid and ethylenediamine tetraacetic acid monosodium salt in 400 ml. of water for injection. Add this solution to the reserpine solution and mix. Bring up to volume with water for injection and stir. Pass nitrogen gas through solution for 30 minutes. Filter solution through medium porosity filter. Fill into 2 ml. amber ampuls or 10 ml. amber vials that have been previously flushed with nitrogen gas. Seal ampuls and stopper and cap vials. Sterilize in autoclave at 10 p.s.i., 115° C. for 30 minutes. pH 3.8.

Example 2

Materials and formula	ml	1000
Reserpine	g	2.500
N,N-dimethylacetamide	ml	100.000
Polyethylene glycol 300	ml	100.000
Adipic acid	g	10.000
Water for injection, q.s.	ml	1000.000

Procedure.—Dissolve the reserpine in the N,N-dimethylacetamide. Add the adipic acid and stir until solution is affected; then add the polyethylene glycol 300 and stir. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

Example 3

Using the identical procedure and composition as that used in Example 1, except that deserpidine (or rescinnamine) is substituted for the reserpine, one may prepare the analogous composition.

Example 4

Materials and formula	ml	1000
Reserpine	g	2.500
N,N-dimethylacetamide	ml	200.000
Adipic acid	g	10.000

Water for injection, q.s. ml 1000.000

Procedure.—Dissolve the reserpine in the N,N-dimethylacetamide. Then add the adipic acid and mix until a solution is obtained. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

Example 5

Using the identical procedure and composition as that used in Example 4, except that deserpidine (or rescinnamine) is substituted for the reserpine, one may prepare the analogous composition.

4
Example 6

Materials and formula	ml	1000
Reserpine	g	2.500
N,N-dimethylacetamide	ml	100.000
Polyethylene glycol 300	ml	50.000
Benzyl alcohol	ml	10.000
Adipic acid	g	10.000
Water for injection, q.s.	ml	1000.000

Procedure.—Dissolve the reserpine in the N,N-dimethylacetamide. Add the adipic acid and mix until a solution is obtained. Then add the polyethylene glycol 300 and benzyl alcohol and stir, until a clear solution results. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

Example 7

Materials and formula	ml	1000
Reserpine	g	2.500
Adipic acid	g	10.000
N,N-dimethylacetamide	ml	100.000
Niacinamide	g	30.000
Propionic acid	ml	10.000
Hydroquinone	g	0.100
Ethylenediamine tetraacetic acid monosodium salt	g	0.100
Benzyl alcohol	ml	10.000
Water for injection, q.s.	ml	1000.000

Procedure.—Dissolve the reserpine in the N,N-dimethylacetamide. Then add the niacinamide and mix until a solution is obtained. Then add the adipic and propionic acids and stir to attain uniformity. Dissolve the hydroquinone and ethylenediamine tetraacetic acid monosodium salt in about 200 ml. of water for injection and add to the reserpine solution and mix well. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

Example 8

Materials and formula	ml	1000
Reserpine	g	2.500
N,N,N',N'-tetramethyl urea	g	100.000
Polyethylene glycol 300	ml	200.000
Benzyl alcohol	ml	10.000
Adipic acid	g	10.000
Water for injection, q.s.	ml	1000.000

Procedure.—Dissolve the N,N,N',N'-tetramethyl urea in 200 ml. of water for injection. Then add the reserpine and dissolve. Add the adipic acid and mix until solution results. Add the polyethylene glycol 300 and benzyl alcohol and mix. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

Example 9

Materials and formula	ml	1000
Reserpine	g	2.500
Adipic acid	g	10.000
N,N-dimethylacetamide	ml	100.000
N,N,N',N'-tetramethyl urea	g	50.000
Benzyl alcohol	ml	10.000
Water for injection, q.s.	ml	1000.000

Procedure.—Dissolve the reserpine in the N,N-dimethylacetamide. Add the adipic acid and mix until solution results. Then add the N,N,N',N'-tetramethyl urea and stir until all dissolved. Add the benzyl alcohol

and mix. Bring up to volume with water for injection. Pass nitrogen gas through finished solution for 30 minutes. Filter solution through a medium porosity filter. Fill into ampuls (or vials) that have been previously flushed with nitrogen gas. Sterilize at 115°, 10 p.s.i. for 30 minutes.

This invention may be variously otherwise embodied within the scope of the appended claims.

What is claimed is:

1. An injectable aqueous solution consisting essentially of an effective amount up to about 10 mg. of a member selected from the group consisting of reserpine, rescinnamine and deserpidine, about 5 to about 30 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl and about 0.5 to about 2.0 percent by weight of a soluble, non-toxic acid of pK_a about 3 to about 5, per milliliter of solution, said N-substituted amide being derived from those selected from the group consisting of urea, thiourea, a saturated lower aliphatic mono-carboxylic acid amide and a saturated lower aliphatic di-carboxylic acid amide.

2. A composition of claim 1, wherein an N-substituted amide is an amide containing two to four substituents on amino nitrogen atoms.

3. A composition of claim 1, wherein an N-substituted amide is an amide containing two substituents on amino nitrogen atoms.

4. A composition of claim 1, wherein an N-substituted amide is an amide containing three substituents on amino nitrogen atoms.

5. A composition of claim 1, wherein the N-substituted amide is N,N-dimethylacetamide.

6. A composition of claim 5, wherein the soluble, non-toxic acid is adipic acid.

7. An injectable aqueous solution consisting essentially of an effective amount up to about 10 mg. of reserpine, about 5 to about 30 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl and about 0.5 to about 2.0 percent by weight of a soluble, non-toxic acid of pK_a about 3 to about 5, per milliliter of solution, said N-substituted amide being derived from those selected from the group consisting of urea, thiourea, a saturated lower aliphatic mono-carboxylic acid amide and a saturated lower aliphatic di-carboxylic acid amide.

8. An injectable aqueous solution consisting essentially of about 1 to about 5 mg. of reserpine, about 10 to about 20 percent by weight of at least one N-substituted amide, each of said N-substituents being members selected from the group consisting of lower alkyl, hydroxy-lower alkyl, phenyl, lower alkyl-phenyl and halo-phenyl and about 0.5 to about 1.5 percent by weight of a soluble, non-toxic acid of pK_a about 3 to about 5, per milliliter of solution, said N-substituted amide being derived from those selected from the group consisting of urea, thiourea, a saturated lower aliphatic mono-carboxylic acid amide and a saturated lower aliphatic di-carboxylic acid amide.

9. An injectable aqueous solution consisting essentially of an effective amount up to about 10 mg. of a member selected from the group consisting of reserpine, deserpidine and rescinnamine, about 5 to about 30 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl, about 0.5 to about 2.0 percent by weight of a soluble, non-toxic acid of pK_a about 3 to about 5 and about 5 to about 30 percent by weight of a poly-lower alkylene glycol having a molecular weight about 300 to about 20,000, per milliliter of solution, said N-substituted

amide being derived from those selected from the group consisting of urea, thiourea, a saturated lower aliphatic mono-carboxylic acid amide and a saturated lower aliphatic di-carboxylic acid amide.

5 10. An injectable aqueous solution consisting essentially of an effective amount up to about 10 mg. of reserpine, about 5 to about 30 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl, about 0.5 to about 2.0 percent by weight of a soluble, non-toxic acid of pK_a about 3 to about 5 and about 5 to about 30 percent by weight of a poly-lower alkylene glycol having a molecular weight about 300 to about 20,000 per milliliter of solution, said N-substituted amide being derived from those selected from the group consisting of urea, thiourea, a saturated lower aliphatic mono-carboxylic acid amide and a saturated lower aliphatic di-carboxylic acid amide.

11. An injectable aqueous solution consisting essentially of about 1 to about 5 mg. of reserpine, about 10 to about 20 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl, about 0.5 to about 1.5 percent by weight of a soluble, non-toxic acid of pK_a about 3 to about 5 and about 5 to about 30 percent by weight of a polyethylene glycol having a molecular weight about 300 to about 20,000, per milliliter of solution, said N-substituted amide being derived from those selected from the group consisting of urea, thiourea, a saturated lower aliphatic mono-carboxylic acid amide and a saturated lower aliphatic di-carboxylic acid amide.

25 12. A composition of claim 11, wherein the N-substituted amide is N,N-dimethylacetamide.

13. A composition of claim 12, wherein the soluble, non-toxic acid is adipic acid.

14. An injectable aqueous solution consisting essentially of about 1 to about 10 mg. of reserpine, about 10 to about 20 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl, about 0.5 to about 1.5 percent by weight of a soluble, non-toxic acid of pK_a about 3.5 to about 4.5, per milliliter of solution, said

30 N-substituted amide being derived from those selected from the group consisting of urea, thiourea, a saturated lower aliphatic mono-carboxylic acid amide and a saturated lower aliphatic di-carboxylic acid amide.

15. An injectable aqueous solution consisting essentially of about 1 to about 10 mg. of reserpine, about 10 to about 20 percent by weight of at least one N-substituted amide, each of said N-substituents being members selected from the group consisting of lower alkyl, hydroxy-lower alkyl, halo-lower alkyl, phenyl, lower alkyl-phenyl and halo-phenyl, about 0.5 to about 1.5 percent by weight of a soluble, non-toxic acid of pK_a about 3.5 to about 4.5 and about 15 percent by weight of a polyethylene glycol having a molecular weight about 300, said N-substituted amide being derived from those

35 selected from the group consisting of urea, thiourea, a saturated lower aliphatic mono-carboxylic acid amide and a lower aliphatic di-carboxylic acid amide.

16. An injectable aqueous solution consisting essentially of about 2.5 mg. of reserpine, about 10 to about 20 percent by weight of N,N-dimethylacetamide and about 0.5 to about 1.5 percent by weight of a soluble, non-toxic acid of pK_a about 3.5 to about 4.5, per milliliter of solution.

40 17. An injectable aqueous solution consisting essentially of about 2.5 mg. of reserpine, about 10 percent

by weight N,N-dimethylacetamide and about 1 percent by weight of adipic acid.

18. An injectable aqueous solution consisting essentially of about 2.5 mg. of reserpine, about 10 percent by weight N,N-dimethylacetamide, about 5 percent by weight polyethylene glycol having a molecular weight about 300 and about 1 percent by weight of adipic acid, per milliliter of solution.
